BANJO MUTE

Application filed April 4, 1930. Serial No. 441,628.

This invention relates to a mute attachment for a banjo which is adapted to mute the tone of the instrument simply by changing the position thereof and without it being necessary for the musician to alter the position of his hands while playing the instrument.

Our Patent No. 1,780,361, granted November 4, 1930, specifies and claims, one form of construction for a banjo mute of this character. The present invention pertains to another construction of a banjo mute of a generally similar character.

The construction described and claimed by the present application, in addition to the objects and advantages of the banjo mute of said patent, possesses the advantage of being composed of a fewer number of parts and of being so constructed that it can be more readily stamped out by means of dies and can be very quickly and easily assembled.

Other objects, advantages and features of invention may hereinafter appear.

Referring to the accompanying drawings which illustrate what is at present deemed to be a preferred embodiment of the invention,

Fig. 1 is an end elevation of the working parts of the device, the position of the membrane or head of the banjo wherein the device is mounted being indicated by dotted lines.

Fig. 2 is a side elevation looking at Fig. 1 from right to left the membrane of the banjo being omitted.

Fig. 3 is a cross section on line 3—3 of Fig. 2.

Fig. 4 is a back view of a complete banjo showing the device mounted therein.

Fig. 5 is a cross section on line 5—5 of Fig. 1.

Fig. 6 is a section on line 6—6 of Fig. 3.

Referring in detail to the drawings, the device comprises a base 7, preferably a rectangular plate, which is supported within the banjo drum 8 either by means of the well known stay rod or "stick" 9 which extends

through the banjo drum D, or by means of a pair of rods 10, the position of one of which is indicated in dotted lines in Fig. 3.

When the device is supported upon the stay rod 9 this is done by means of the channel iron clamping members 15 and 16 each of which is provided at each side with an outwardly directed flange 17, said members 15 and 16 being provided with clamping screws 18 preferably four in number. The preferred form of clamping screw, as shown in the drawings, is provided with a diametrically reduced threaded end portion 18a which screws through a threaded hole in one of the flanges 17, the body portion 18b of said screw abutting against the lower side of the other flange 17.

The uppermost clamping member 15 is provided with an upwardly projecting screw-threaded stud 20 which is formed integral therewith. Said stud 20 projects upwardly through a transverse slot 21 provided in the base plate 7. An internally threaded sleeve 23 provided at its upper end with a thumb nut 24, is screwed on to said stud. This arrangement makes it possible to shift the clamping members 15 and 16 to the right from the position shown in Fig. 3 until they are located at the mid-width of the base plate 7, in which position a space is provided

between each of the flanges 17 of the member 15 and the bottom of the base plate 7 wherein to clamp the bars 10 when said bars are used. When the thumb nut 24 is so rotated as to unscrew the sleeve 23 from the stud 20 the member 15 may be dropped to a lower position than that shown in Fig. 3, whereupon one of the bars 10 may be inserted at each side thereof above the flanges 17 and then the device may be clamped upon said bars by tightening the thumb nut 24. When so used the channel member 16 can be eliminated.

Supported by said base plate 7 at one side thereof is the pendulum 27, and supported by

85

90

said base plate at the other side thereof is the mute proper 28 which, in the present embodiment of the invention, is preferably approximately elliptical. There is an operative connection between said pendulum 27 and said mute 28, said connection being shown as including an actuating arm 30 with which cooperates a companion arm or lever 31. Said arm 30 is pivoted between its ends by a pivot screw 30s to an upstanding flange 7a with which the base plate 7 is provided at one end.

The mute proper 28 is shown having secured to the back side thereof an attaching member 32 which is T-shaped in cross section and which has at each side a base flange 33 which is attached by screws 34 or otherwise to the mute proper. The outstanding portion of said member 32 has pivoted thereto, by the pivot screw 35, the adjacent end of the lever 30, the distance between the pivot screws 35 and 30s being less than the distance between said screw 30s and the pivotal connection at the other end of said lever 30, which will next be described.

The connection for said lever 30 comprises an upwardly extending rod 37 the lower end of which is, by means of a clip 38 and pivot screw 39, pivotally connected with the pendulum 27. Said clip 38 has at its upper end a laterally extending apertured ear 38a through which the lower headed end of the rod or bolt 37 extends.

A head or clip 40 is provided with an eye through which the bolt 37 extends. Said head 40 has an extension 41 whereby it is secured, by means of a screw 42, to the adjacent end of the aforementioned lever 30. Said screw 42 not only is a clamping screw to secure said head to said lever 30, but also operates as a pivot point about which said head may be adjusted to the desired position with respect to lever 30 and then be clamped rigidly to said lever. The use of said head 40 and its attaching screw 42 renders this part of the device replaceable when necessary.

Between said head 40 and the aforementioned clip 38 the bolt 37 is provided with a compression spring 45, said bolt also being provided with, and extending through, an upper follower 46 and a lower follower 47. Said followers 46 and 47 are each so shaped as to form seats around which the adjacent ends of the spring 45 are coiled, as will be understood from Fig. 6. The outer ends of each of these followers are convex, thus forming a limited universal joint connection near each end of the bolt 37, it being understood that the openings through the ear 38a and through the head 40 are each large enough to permit a limited universal swinging of said bolt. A thumb nut 48 screwed on to the upper end of the bolt 37 completes the connection between the pendulum 27 and the adjacent end of the lever 30. The compression

spring 45 holds the followers 46 and 47 in the proper operative position.

The arm 31 which cooperates with arm 30 is also operatively related both to the pendulum and to the mute proper 28. In a general way said arm 31 may be said to extend in parallelism with its companion arm 30. One end of arm 31 is pivoted to the upstanding flange 7a of the base plate by means of a pivot screw 56, and the other end of said arm 31 is pivotally related to the mute proper by means of the pivot screw 57 screwed into the member 32 carried by said mute proper.

It will be observed that the distance between the pivot screws 56 and 57 of the arm 31 is greater than the distance between the supporting pivot 30s of the arm 30 and the pivot 35 whereby said arm 30 is connected with the mute proper. The result of this construction is that when the operating arm 30 is oscillated by the pendulum 27 the upper portion of the mute proper 28 will be moved farther toward and from the banjo membrane, indicated at 60, than will the lower portion of said mute proper.

These levers are so adjusted with relation to the mute proper that when contact is made with the banjo member the mute will squarely abut against said banjo membrane, but when the mute is withdrawn from the membrane, the top of the mute will be farthest from the membrane.

The arm 30 is provided with a foot portion 30f at the end thereof which is pivoted to the mute proper. The pivot screw 35 extends through said foot portion between its toe *t* and heel *h*, thus positioning said toe and heel to act as stops when they engage the adjacent face of the mute proper 28.

Referring now to certain details with regard to the construction of the pendulum 27, said pendulum is shown as consisting of a plate of a generally tri-angular shape provided with a pair of parallel arms or studs 63 and 64 which are spaced apart from each other as shown in Fig. 1, and a pendulum weight 65 slidably adjustable upon said arms. Said weight 65 may be provided with a set screw 66 which cooperates with the stud 63 to secure said weight 65 in its adjusted position at the desired distance from the body portion or plate 27 of the pendulum. The object of providing this adjustment for the weight 65 is to permit said weight to be adjusted to a point where it will not come in contact with the supporting rod or stay 9 during the operation of the device. When the device is mounted upon the pair of rods 10 which may be used instead of the stay or rod 9, the pendulum weight 65 may be so adjusted as to pass between said rods.

The face of the mute proper 28 is preferably covered with a rubber layer 70 which is secured thereto in any suitable manner. To the outer side of said rubber layer 70 may be

adhered or otherwise secured a felt coat 71 thereby providing a surface which may repeatedly be brought into contact with the banjo member 60 without injuring said membrane.

In Figs. 3 and 5 the channel iron members 15 and 16 are shown provided with an inner facing 73 which adapts them to be forcibly clamped down upon the stay rod 9 without marring said rod.

By oscillating the banjo while it is being played and at the same time is being held in such a position that the mute proper is only in approximate contact with the banjo membrane, a relative oscillation is produced between the pendulum and the parts operatively connected therewith, thus causing the mute proper to repeatedly engage and disengage the banjo membrane thereby producing a vibrato tone effect.

When the player desires to maintain the banjo in as nearly a vertical position as possible, he will screw down the nut 48 upon the bolt 37 against the opposition of the spring 45, which will so regulate the position of the pendulum that it will operate the mute proper as desired even though the banjo be only slightly moved toward the horizontal position. When the said nut 48 is loosened the adjustment of the pendulum becomes such as to permit the player to hold the instrument in a more nearly horizontal position.

Claims:

1. In combination with the head and membrane of a banjo, a mute, means to support said mute within said head in an operative relation to said membrane, a pendulum, means pivotally connecting said pendulum to said head, and means operatively connected with said pendulum to operate said mute, said last recited means comprising a pair of arms which extend in a general parallel direction with relation to each other and both of which are pivotally related to said mute.

2. A banjo mute of the character described comprising a pendulum, a mute proper, an operating arm pivotally related both to said mute proper and to said pendulum, means for pivotally supporting said operating arm between its ends, and a companion operating arm which is provided with a fixed pivot at one end and which has its other end pivotally connected with said mute proper, and means to operatively support the aforementioned parts within the head of the banjo.

3. A banjo mute of the character described comprising a pendulum, a mute proper, an operating arm pivotally related both to said mute proper and to said pendulum, means for pivotally supporting said operating arm between its ends, and a companion operating arm which is provided with a fixed pivot at one end and which has its other end pivotally

connected with said mute proper, the distance between the pivotal mounting of the first named operating arm and its pivotal connection with the mute proper being less than the distance between the two pivots of its companion operating arm, and means to operatively support the aforementioned parts within the head of the banjo.

4. In a banjo mute construction, the combination with the stay rod of a banjo, of a mute proper, a pendulum, a support, an operating connection between said pendulum and mute proper mounted upon said support, means for securing said support to said stay rod, and a pendulum weight mounted upon said pendulum, said pendulum weight being adjusted with relation to said pendulum and in a direction which extends transversely with relation to the plane occupied by said stay rod.

5. In a banjo mute construction, a support, a lever or rod pivotally secured between its ends to said support, a pendulum pivotally mounted upon said support, a mute proper carried by one end portion of said arm, and a universal joint connection between the other end of said arm and said pendulum, said joint connection comprising a rod the end portions of which extend through apertured connections, and a compression spring occupying the portion of said rod intermediate of said connections.

6. A banjo mute of the character described comprising a pendulum, a mute proper, an operating arm pivotally related both to said mute proper and to said pendulum, means for pivotally supporting said operating arm between its ends, said operating arm having a foot at the end thereof which is pivotally related to said mute proper the toe portion of said foot contacting with said mute proper to limit the movement of said arm in one direction and the heel portion of said foot contacting with said mute proper to limit the movement of said arm in the opposite direction.

7. A banjo mute of the character described, comprising a support adapted for mounting within a banjo head, an operating arm pivotally mounted between its ends upon said support, a mute proper operatively connected with one end of said operating arm, and a pendulum operatively connected with the other end of said operating arm, the operating connection between said pendulum and operating arm comprising a threaded rod, a compression spring around said threaded rod, and an adjustable nut on said threaded rod, the adjustment of said nut adjusting the length of the connection of which it forms a part and thereby determining the position in which the banjo must be held to cause the mute proper to perform its function.

8. A banjo mute of the character described comprising a pendulum, a mute proper, an operating arm pivotally related both to said mute proper and to said pendulum, means for pivotally supporting said operating arm between its ends, said operating arm having a stop portion at the end thereof which is pivotally related to said mute proper to limit the movements of said mute proper.

10 In testimony whereof we hereunto affix our signatures.
